US0D1010093S

(12) **United States Design Patent** (10) **Patent No.:** **US D1,010,093 S**
(45) **Date of Patent:** **** Jan. 2, 2024**

(54) **PORTABLE DESKTOP USB FAN**

(71) Applicant: **Weibin Xie**, Fujian (CN)

(72) Inventor: **Weibin Xie**, Fujian (CN)

(**) Term: **15 Years**

(21) Appl. No.: **29/824,294**

(22) Filed: **Jan. 24, 2022**

(51) LOC (14) Cl. **23-04**

(52) U.S. Cl.

USPC **D23/370**

(58) **Field of Classification Search**

USPC D23/314, 335, 328, 332, 370-379,
D23/381-385, 411-414, 360

CPC . F04D 5/00; F04D 27/00; F04D 25/10; F04D
29/64; F04D 19/00; F24H 3/04; B65D
71/00

CLAIM

The ornamental design for a portable desktop USB fan, as shown and described.

DESCRIPTION

FIG. 1 is a top perspective view of the portable desktop USB fan showing my new design.

FIG. 2 is a front view of the portable desktop USB fan.

FIG. 3 is a rear view of the portable desktop USB fan.

FIG. 4 is a left side view of the portable desktop USB fan.

FIG. 5 is a right side view of the portable desktop USB fan.

FIG. 6 is a top view of the portable desktop USB fan.

FIG. 7 is a bottom view of the portable desktop USB fan.

FIG. 8 is an enlarged view of the FIG. 2; and,

FIG. 9 is an enlarged view of the FIG. 3.

Any shading and cross-hatching are not features of the design but are utilized to illustrate the surface contours of the portable desktop USB fan design in the drawings.

1 Claim, 9 Drawing Sheets
